UNITED STATES PATENT OFFICE.

CLEYSON L. BROWN, OF ABILENE, KANSAS, ASSIGNOR TO UNITED SECURITIES COMPANY, OF ABILENE, KANSAS, A CORPORATION OF KANSAS.

ELECTRIC SWITCH.

Application filed May 13, 1925. Serial No. 30,015.

My invention relates to electric switches of the type employed to automatically interrupt high voltage circuits and is particularly adapted for use in high voltage transmission lines incident to the distribution of current for domestic use in rural communities.

It will be understood, however, that my improved switch is in no way limited to use in connection with high voltage circuits incident to the distribution of current in rural communities, but on the contrary can be used with facility in any locality or under any conditions where high voltage current is transformed into low voltage current.

It is the purpose of my invention to provide a switch of the general type referred to which will efficiently meet the requirements imposed by rural conditions, which will effectively protect the transformers and other elements incident to the distribution of current for domestic use over high voltage lines; which will enable the fusing element thereof to be replaced by unskilled labor at relatively small expense; which will permit removal and replacement of the fuse blade from and to the switch by inexperienced persons without danger; which will be substantially "fool proof"; and which will be exceedingly simple in construction and inexpensive to produce.

In the drawings chosen to illustrate my invention, the scope whereof is set forth in the claims:

Figure 1 is a perspective view showing my improved switch suspended from the usual supports;

Figure 2, a view partly in section and partly in elevation of what is shown in Figure 1, with the fuse blade of the switch detached and carried by a specially designed fuse blade removal and replacement stick;

Figure 3, a side view of the switch;

Figure 4, a section on the line 4-4 of Figure 3; and

Figure 5, a detail perspective view of one end of the fuse blade.

Referring to the drawings my improved switch is shown as comprising a bar 10 secured transversely of cross arms 11-11 supported from a suitable line pole (not shown). Carried by the bar 10 are spaced insulators 12-12 from each of which depends a post 13 of any suitable material.

Secured to each post 13 is a depending metallic contact member 14 which terminates at its lower end in a hook-shape formation 15 opening upwardly with respect to the insulator 12 and post 13.

My improved switch is completed by a fuse blade A bridging the contact members 14 and having its end portions detachably engaged in the formations 15 as will be apparent. In detail the fuse blade A comprises an elongated insulating body portion 16, which, for the sake of cheapness and durability when subjected to rough usage, I preferably form of suitable wood. Extending longitudinally through the portion 16 is a passage 17 which opens laterally at each end through one side of said portion 16 as at 18. Secured against the side of the portion 16 through which the passage 17 opens laterally are metallic contact plates 19 which are disposed just above respective lateral openings 18 and project respectively beyond the ends of the portion 16 for direct detachable engagement in the hook-shaped formations 15. The plates 19 are electrically connected by a fuse wire 20 which extends through the passage 17 and lateral openings 18.

To provide for the easy and safe removal and replacement of the fuse blade A from and to the hook formations 15, I secure centrally of the body portion 16 a depending insulator pin 21 having the usual threads 22. When it is desired to remove the fuse blade A the operator employs a removal and replacement stick indicated generally in Figure 2 at B. This stick embodies a suitable handle 23 on one end of which is secured a two-piece clamp 24, said clamp in turn holding an insulator 25 having a threaded recess 26 whereby the operator, by rotating the handle 23 in the proper direction can screw the insulator 25 on the pin and thus secure the stick to the fuse blade. When the stick is thus secured to the fuse blade, the operator by pushing upwardly can easily and with perfect safety effect detachment of the fuse blade from the formations 15 and then lower said blade for the purposes desired. The manner of replacing the blade through the medium of the stick B will be obvious, it being noted in this connection that the hook-shaped formations 15 render the proper replacement of the blade exceedingly simple and certain in that it

is only necessary for the operator to position the contact plate 19 just above the mouths of respective formations 15 and then pull downwardly on the stick B. In this operation the application of excessive downward pull on the stick can in no way result in a faulty assembly between the blade and the other portions of the switch, this in contradistinction from those switches of this type in which different directional movements must be imparted to the fuse blade to effect either its removal or its replacement. It will also be noted in connection with the upwardly opening hook-shaped formations 15 that when the fuse blade A is applied to the switch all possibility of the same becoming accidentally detached from the switch is eliminated owing to the fact that only upward movement of the blade can effect its detachment from either formation 15.

I claim:

1. A combined fuse and switch structure comprising insulated supporting means, a fuse blade, means for suspending said fuse blade from said supporting means comprising a pair of terminal members depending from said supporting means, and means at the lower ends of said terminal members for detachably connecting the fuse blade thereto, whereby the fuse blade, when operatively

applied, will be disposed at the lowermost end of the structure.

2. A combined fuse and switch structure comprising insulated supporting means, a fuse blade and means for suspending said fuse blade from said supporting means comprising a pair of terminal members depending from said supporting means, said terminal members each having their lower ends formed to provide hook-shaped blade receiving portions with said portions opening upwardly, whereby the fuse blade when operatively applied, will be disposed at the lowermost end of the structure.

3. A combined fuse and switch structure comprising insulated supporting means, a fuse blade, means for suspending said fuse blade from said supporting means comprising a pair of terminal members depending from said supporting means, said terminal members each having their lower ends formed to provide hook-shaped blade receiving portions with said portions opening upwardly, and means depending from said blade, when the latter is applied, with which a blade removing and replacing implement is adapted to be detachably connected.

In testimony whereof I hereunto affix my signature.

CLEYSON L. BROWN.
